UNITED STATES PATENT OFFICE.

ARTHUR JAMES POSTANS, OF BRENTFORD, ENGLAND.

STROPPING AND LIKE MACHINE.

1,075,938.

Specification of Letters Patent.

Patented Oct. 14, 1913.

Application filed November 5, 1912. Serial No. 729,586.

To all whom it may concern:

Be it known that I, ARTHUR JAMES POSTANS, a subject of the King of England, residing at Brentford, Middlesex, England, have invented certain new and useful Improvements in Stropping and like Machines, of which the following is a specification.

This invention is for improvements in or relating to stropping and like machines of the type wherein a machine is reciprocated relatively to a band or vice versa and contains parts which are so engaged by the band that the relative movement of the machine and band causes a buffing member to be rotated and a blade-holder to be rocked to bring the blade which is to be stropped or sharpened first against such buffing member and then away from it.

The present invention consists in the specific construction of a machine of this type wherein there is combined with a driving pulley having positive operative combination with the buff-spindle and a driving pulley for a blade-holder of a friction device interposed between the last-mentioned driving pulley and the blade-holder so that slip can occur between these two parts whereby the degree of pressure of the blade against the buff is always maintained constant.

In the preferred construction the buff is made narrower than the blade and one of them, for example the buff, is traversed along in the known manner by means of a worm-feed.

Another feature of the construction consists in arranging this worm-feed within the handle of the apparatus.

Another feature of the invention consists in the construction of the casing comprising two separable parts between which pulleys are mounted and which provide bearings for the blade-holder and buff-spindle that project through from one side of the casing. To give the driving-band sufficient grip upon the pulleys, a third pulley staggered relatively to the other two is preferably employed, so that by deflecting the band around this third pulley it may be made to engage a larger surface of the other two pulleys than would be the case if the third pulley were absent.

In the accompanying drawings which illustrate one method of carrying out this invention:—Figure 1 is a perspective view of the machine; Fig. 2 is a horizontal sec-

tion through the same in the plane of the blade-holder and buff-spindles; Fig. 3 is a section on the line 3—3 of Fig. 2; Fig. 4 is a section on the line 4—4 of Fig. 2; Fig. 5 is a section through the blade-holder showing the method of securing the blade therein, and Fig. 6 is a side elevation of a modified form of the apparatus which also falls within the scope of this invention.

Like letters indicate like parts throughout the drawings.

The casing of the apparatus comprises two separable parts A, A¹ respectively. The part A is recessed to receive two driving-pulleys B and C and an idle pulley D, and the two parts together provide bearings for the blade-holder spindle E and buff-spindle F. These two spindles project from the casing on one side and within the casing extend through the pulleys B and C respectively. The pulley B has a hollow cylindrical extension B¹ on one side which lies in a recess formed in an extension A² on the part A of the casing. The spindle E projects into this extension and is prevented from endwise movement by a washer and screw E¹ E² let into a recess in the extension. A plug A³ is screwed into the recess in the end of the extension E¹ which recess is made to receive the washer and screw E¹ E². The pulley B is prevented from axial movement by the sides of the casing and the extension A² and the casing supports it by providing a bearing for the extension B¹ on the pulley. Driving connection between the spindle and the pulley is of a frictional character and is effected by three loose resilient strips or plates E⁴ which are so mounted in the hollow extension B¹ that they bear against the interior walls of the extension and also against the spindle E, being arranged in the form of a triangle as is clearly shown in Fig. 4.

The idle pulley D is mounted on a pin D¹ fast to the casing portion A and is offset relatively to the pulleys B and C.

The spindle F carries a circular buff F¹ and passes through the pulley C into an extension A⁴ on the casing part A which extension carries a hollow handle G. Mounted in the extension or formed therein is a tube or sleeve X having a worm A⁵ and the spindle F has fast on it a pin F² that operates with the worm. Fast on the pulley C is a lug C¹ and carried by the spindle F is a collar F³ having a lug F⁴. The collar

F³ has in it a feather F⁵, Fig. 4, which engages a groove F⁶ in the spindle F so that the spindle can move axially through the collar although the collar and spindle must 5 rotate together as one; the collar is prevented from endwise displacement on one side by the pulley C and on the other side by butting against the worm portion A⁶.

The blade-holder is constituted by an enlarged end E⁵ on the spindle E which end 10 is slotted at E⁶ and the extreme end is recessed at E⁷. Traversing the slot at the end nearest the casing is a pin E⁸ and entered in the recess E⁷ at the opposite end is a ball 15 E⁹ which projects into the slotted portion and is kept in position by a spring E¹⁰ that in turn is held in place by a cap E¹¹ screwed over the enlarged end E⁵.

The blade H to be used with this strop 20 has a notch H¹ at each end and when the blade is in position in the holder as shown in Figs. 2 and 5, one notch engages the pin E⁸ and the other the spring-controlled ball E⁹. The two parts A A¹ of the casing may 25 be held together by screws for which the holes J are shown in the part A, Fig. 3. The part A¹ thus constitutes a cover-plate which can be removed after releasing the screw E² whereupon all the parts can be 30 drawn out from the other portion A of the casing.

A driving-belt K which is non-continuous, is passed through a hole K¹ in one side of the casing, around one side of the 35 pulley B, thence around the idle pulley D, from which it passes around one side of the pulley C and leaves the casing by another hole K². The end of this belt may be provided with any convenient means for holding it, such as a couple of rings, one at each 40 end, or loops, or a ring K³ and loop K⁴.

The operation of this device is as follows:—To insert a blade in the holder, one end is first introduced into the slot E⁶ so 45 that its notch H¹ is made to engage the pin and then the blade is turned about this pin so that the other end is pushed past the ball E⁹ whereupon the latter snaps into the notch H¹ at that end of the blade and thereby 50 cures the blade in the holder. One end of the band K, for example the loop K⁴, is then hooked over any convenient support and the operator holds the ring K³ in his hand and pulls the band tight. By means of the 55 handle G the whole device can then be traversed backward and forward along the band K. With the parts in position shown in Figs. 1 and 2, the machine is being traversed toward the ring K³ and has nearly 60 reached the end of the operative portion of its travel. The pulley C is being rotated in the direction of its arrow, Fig. 3, and the lug C¹ is therefore kept up against the lug F⁴ of the sleeve F². This sleeve by means 65 of its key F⁵ is therefore rotating the buff-

spindle F, and the pin F² carried by the spindle is traversing the worm A⁶ so that the spindle is traveling outward from the casing A A¹ toward the end of the blade H. Simultaneously the movement of the machine along the belt K is attempting to rotate the pulley B in the direction of the arrow placed beside it in Fig. 3, and by means of the friction device E⁴ a torsional strain 70 is put upon the spindle E which keeps the edge of the blade H pressed against the buff F¹. As the buff travels along the edge of the blade and at the same time rotates against it, the whole of the edge is stropped. When the buff-spindle F comes to the end 80 of its travel, the pulley C will merely slide along the driving-band K if the machine is still moved toward the ring K³, but as the resistance to movement is doubled by this sliding, the operator immediately feels the 85 check and commences to move the machine in the opposite direction, that is, toward the loop K⁴. At the first movement in the reverse direction, the pulley B rotates in a direction opposite to that indicated by its 90 arrow, Fig. 3, and thus rocks the blade-holder in such direction as to swing the blade over until its opposite edge rests against the buff F¹. During the whole, or at all events, the earlier part of this movement, the buff is stationary because the direction of rotation of its pulley C is also 95 reversed and therefore the operating lug C¹ is carried away from the lug F⁴ and has to be carried through a considerable part of 100 a revolution before it comes into contact with the opposite side of the lug F⁴. As soon as it does again come into contact with the lug, the spindle F commences to rotate in the direction opposite to that in which it was traveling when the blade was in the other position, so that it now rotates in such 105 direction as to strop the blade in its new position and commences to travel from left to right of Fig. 1 instead of right to left as before. The buff continues thus to rotate and travels along the blade until it reaches the end of the same, when the machine being again reversed, the same reversal of the parts takes place and that side of the blade 110 originally stropped is again stropped. This reciprocation of the machine and the corresponding reversal of the parts can be carried out rapidly and for any length of time until a satisfactory edge has been produced 115 on the razor-blade, after which the blade can be removed by merely pulling that end forward which is held by the ball, whereupon it will be released from the holder.

In the case of double-edged razors, it may 120 be desired to strop both the edges simultaneously. For this purpose two buffs L, L¹ would be employed each mounted on spindles L² similar to the spindle F and provided, each, with a driving pulley L³ and worm 125

feed mechanism as described with reference to the spindle F. The blade-holder M would be mounted between the two buff spindles and arranged to carry the double-edged 5 blade in any convenient manner, which there is no need to describe in detail as such holders are well-known and the holder in itself forms no part of the present invention. The spindle of the holder instead of carrying 10 a pulley would carry a toothed wheel M¹ and this would engage with a second toothed-wheel M² mounted direct or upon a part secured to an idle pulley M³. The idle pulley would be staggered relatively to the 15 pulleys L³ and the driving-band N passed around the pulleys L³ and idle pulley M³ in the manner shown in Fig. 6. It will be seen that by traversing this machine along the band N in the same way as has been described 20 with reference to the other forms shown in Figs. 1-5, the buffs will both operate, simultaneously, in the same manner as the buff F¹ and the blade-holder will rock at each reciprocation to bring the opposite sides 25 of the blade against the buffs. A friction-device will of course be inserted between the spindle of the blade-holder and the toothed wheel M¹ in the same manner as was provided between the spindle E and the blade- 30 holder E⁵ and its pulley B.

Obviously any kind of blade can be stropped with the machine described in this invention, the holder therefor being shaped according to the blade as is common practice in stropping devices.

What I claim as my invention and desire to secure by Letters Patents is:—

1. In a stropping machine, the combination of a casing constructed to provide a handle; a spindle mounted to rotate in said casing and constructed to hold the blade to be sharpened; a pulley journaled in said casing and having frictional driving engagement with the spindle; a tube mounted in the casing handle and formed with a spiral groove; a spindle mounted to rotate in said tube and having a part engaging within the spiral groove thereof whereby to reciprocate said spindle; a pulley having splined connection with said last named spindle; a buffer mounted on said spindle and means for operating said pulleys.

2. In a stropping machine, the combination of a casing constructed to provide a handle; a spindle mounted to rotate in said casing and constructed to hold the blade to be sharpened; a pulley journaled in said casing and having frictional driving engagement

ment with the spindle; a tube mounted in the casing handle and formed with a spiral 60 groove, a spindle mounted to rotate in said tube and having a part engaging within the spiral groove thereof whereby to reciprocate said spindle; a collar splined on said spindle and provided with a lug; a pulley journaled 65 on the spindle and having a lug adapted to engage with said collar lug for rotating the spindle; a buffer mounted on said spindle; and means for operating said pulleys.

3. In a stropping machine, the combination of a casing constructed with a hollow handle; a pulley having a cylindrical extension journaled in the casing; a blade holding spindle journaled in the casing; resilient plates mounted in said cylindrical extension 70 and having frictional driving engagement with the spindle; a tube mounted in the casing handle and formed with a spiral groove; a spindle mounted to rotate in said tube and having a part engaging within the spiral 75 groove thereof whereby to reciprocate the spindle; a collar splined on the spindle and provided with a lug; a pulley journaled on the spindle and having a lug adapted to engage with either side of the collar lug for 80 rotating the spindle; a buffer mounted on said spindle; an idler pulley journaled in the casing adjacent said spindle pulleys; and a belt passing through the casing and engaging with all of said pulleys for operating 85 the same.

4. In a stropping machine, the combination of a separable casing comprising two sections, one of said sections providing recesses; a pair of spindles journaled in said 90 casing and having portions projecting to one side thereof and disposed in parallel relation, one of said spindles constructed to hold the blade to be sharpened; a buffer mounted on the other of said spindles; a pulley journaled in one of said chambers and having frictional driving engagement with said blade holding spindle; a pulley journaled on the buffer spindle and having driving engagement therewith; means for causing the 105 buffer spindle to reciprocate; and a belt passing through the casing and having engagement with said pulleys for operating the same.

In testimony whereof I have signed my 110 name to this specification in the presence of two subscribing witnesses.

ARTHUR JAMES POSTANS.
